UNITED STATES PATENT OFFICE.

ALOYSIUS WILHELMUS FRANCISCUS WEYERS, OF TILBURG, NETHERLANDS.

DOWNDRAFT-KILN.

1,379,324.

Specification of Letters Patent. Patented May 24, 1921.

Application filed April 24, 1920. Serial No. 376,343.

To all whom it may concern:

Be it known that I, ALOYSIUS WILHELMUS FRANCISCUS WEYERS, a subject of the Queen of the Netherlands, and residing at 31 Stationsstraat, Tilburg, the Netherlands, have invented certain new and useful Improvements in and Relating to Downdraft-Kilns, of which the following is a specification.

This invention relates to down draft kilns 10 suitable for use in the manufacture of bricks, tiles and analogous ware.

The kilns referred to are often heated by a number of fires on stepped grates. In this system of kilns said fires receive under- 15neath the grate air or air and combustion gases from the adjacent oven chamber or section. If owing to low grade fuel being used the grate is choked by clinker, the air supply is cut off and combustion is entirely 20 prevented. As a result the required temperature will not be obtained and the burning process will be greatly extended. It is practically impossible to sufficiently remove the clinker from the stepped grates when in 25 use.

According to the present invention the stepped grates are replaced by producers, the latter just as the stepped grates receiving the fuel through fire-holes provided 30 thereabove. The air in the usual manner drawn in from the chambers to be cooled or the excess of air together with the combustion gases from a previously fired kiln passes past said producers and (or) partly 35 through the same.

It is advantageous to provide above each producer or retort a guide to the effect that the air ascending past the producer will be forced to pass over the latter. As a result 40 thereof said air is mixed with the gases ascending from the producer, in this manner a complete combustion being effected. No matter how the producer works, as a furnace, a retort or even as a simple fuel 45 trough containing cokes, the air will always find its way to effect the combustion adapted for the manner of firing.

Each producer is preferably provided with a furnace plate with ash-hole, or with 50 only a few ash holes, it being possible to keep the latter open when in use by means of a fire-iron which is inserted through the fire-holes. An inconvenient entering of

cold fresh air is not necessarily connected with said clearing of the ash-holes. 55

As the producers do not prevent the admission of air to the produced gases, the combustion in the producer will proceed even when the ash-hole (or ash-holes) is entirely choked up with clinker, in which 60 case the producer acts as a retort; for the air can also pass past the producer and in this way enter the combustion space. On account of the free admission of air to the upper part of the combustion chamber, the 65 coal in the producer-retort can even oxidize, thus making room for the supply of new fuel. Toward the end of the firing period it is even desirable to remove the clinker only partly or not at all from the 70 furnace plate below the producer, in order to obtain thereby a still more uniform heat supply and in consequence thereof a more perfect control of the temperature.

Generally taken the firing in an oven or 75 kiln according to this invention can be better regulated than in the present kilns. The combustion is more complete, so that in a brick kiln a more uniform burning of the goods will be obtained. The kiln is especially adapted for the making of uniformly 80 colored products, as a smokeless combustion can be obtained.

It has previously been suggested to feed fuel into a shaft at its lower end provided 85 with an inclined tunnel and opening therewith into the adjacent chamber. Said shaft has, however, been made in the solid brick-work and can easily become choked up. In order to have the air nevertheless flow from 90 one chamber into the other, separate air channels which can be shut off by a valve have been provided in the brickwork. It is clearly evident that in such a system the combustion cannot be regulated, under cer- 95 tain circumstances combustion being entirely impossible, for the shafts cannot act as retort or producer and have their gases mixed with the air.

Reverberatory ovens or kilns with a flat 100 grate and charging holes provided thereabove through which the grate may apparently be cleared are also known. It must be admitted, however, that said grate too can become choked up in which case a system of separate flues with valves is required 105

to provide a passage for the air. Kilns of this type are even more liable to give trouble when in use than ovens with stepped grates.

On the accompanying drawing the invention is illustrated by way of example.

Figure 1 is a vertical section on the line C D of Fig. 2 of the firing chamber with producers according to the present invention.

Fig. 2 is a vertical section perpendicular to the cross section according to Fig. 1 and on the line A B in said figure.

The chambers 3 contain the goods to be burned, *e. g.* bricks; the combustion gases are introduced into the upper parts of said chambers through the flame holes 4 defined between the baffles 4^a. The fuel is fired in the producers 5; it receives air from the ash chute 6 through the slag- or ash-hole 7 and the side-holes 8, whereas the gases ascending from the producers are burned by means of air (or combustion gases mixed with an excess of air) passing through the openings 9. This pre-heated air is admitted through the flues 10 opening into the adjacent oven chamber.

It appears from Fig. 1 that the air (or the gas mixture with excess of air) supplied through the flues 10 is divided and enters partly as primary combustion air into each producer, the remaining part reaching the producer gas as secondary combustion air after flowing past the producers. In case the holes 7 become choked up and even when the holes 8 are also choked up, still a sufficient combustion of the gases can take place and oxidizing of the carbon is still possible. However, a choking up of the holes 7 must not necessarily take place for by means of a fire-iron inserted through the fire-hole 11 said holes 7 can be reached and cleared.

In the wall between the producer space and the oven chamber removable fireproof mold bricks 12 are placed which can be removed for inspecting the producer or for the purpose of renewing the producer walls, when the concerned chamber of the oven is cooled down.

In case fuel containing a high percentage of ash is used, in the ash chute a valve may be provided, through which the ash-holes below the producers are cut off from the air supply, it in this manner being possible to remove the ash without admitting cold air. Usually such a cut-off valve, will, however, be superfluous.

From the foregoing it appears that an oven or kiln provided with the described producers has a greater safety of working than an oven with stepped grates, while moreover, as already mentioned in the introduction, the temperature can be regulated more exactly. It is further a not to be underrated advantage that the oven

works with a long flame, on account thereof of a more uniform temperature being obtained in the kiln. The difference with the working with stepped grates is obvious especially in the kiln heated to the highest 70 temperature, for on said grates the fuel must be supplied repeatedly and in small quantities, as there an excess of air pre-heated to a very high degree is used. This will result in a repeated violent blazing up 75 of the flame and a corresponding change of the temperature. With a producer-oven according to the present invention smokeless firing is secured, an economy of fuel in comparison to other ovens being obtained 80 thereby.

It is self-evident that the present invention is applicable not only to chamber ovens or kilns, but also to Hoffman kilns.

Having now particularly described and ascertained the nature of my said invention and in what manner the same is to be performed, I declare that what I claim is:—

1. In a kiln, independent adjoining apartments with intervening walls between them, 90 passages in said walls, fire chambers arranged in the apartments having air admitting openings in their lower portions and open upper ends, said fire chambers being arranged in spaced relation to provide vertical air passages therebetween.

2. In a kiln, independent adjoining apartments with intervening walls between them, 100 passages in said walls, fire chambers arranged in the apartments having air admitting openings in their lower portions and open upper ends, said fire chambers being arranged in spaced relation to provide vertical air passages therebetween and baffles for deflecting air across the open tops of 105 the fire chambers.

3. In a kiln independent adjoining apartments with intervening walls between them, 110 passages in said walls, fire chambers arranged in the apartments having air admitting openings and ash-holes in their lower portions and provided with open upper ends, and spaced baffles arranged above the fire chambers said apartments having fuel supply openings aligned with the ash-holes 115 and the space between the baffles to facilitate clearing of the latter.

4. In a kiln, independent adjoining apartments with intervening walls between them, 120 passages in said walls, fire chambers arranged in the apartments having air admitting openings in their lower portions and open upper ends, said fire chambers being arranged in spaced relation to provide vertical air passages therebetween, and baffles partially obstructing said vertical air passages arranged to deflect air across the open tops of the fire chambers.

5. In a kiln, independent adjoining apartments with intervening walls between 130

them, passages in said walls, fire chambers arranged in the apartments having air admitting openings in their lower portions and open upper ends, said fire chambers being arranged in spaced relation to provide vertical air passages therebetween, and baffles arranged above the vertical air pas-

sages each provided with oppositely inclined faces disposed to deflect air laterally in opposite directions across the upper 10 open ends of the two adjacent fire chambers.

In testimony whereof I affix my signature.

ALOYSIUS WILHELMUS FRANCISCUS WEYERS.
